EASY CLEANING BATHTUB

Genevieve C. Vieyra, Gabbs, Nev.

Application September 2, 1943, Serial No. 500,963

2 Claims. (Cl. 4—173)

This invention relates to a bathtub.

A primary object is to provide a novel construction whereby water discharged into the tub for flushing or cleaning purposes will flow the entire length of the bottom of the tub and over the entire bottom, aiding in loosening dirt or foreign matter, flushing out the same as well as soapy water, and avoiding the necessity of forcing water along the bottom of the tub when rinsing.

It also is aimed to provide a novel structure wherein the tub bottom inclines from the end where the water is introduced, to the base of the inclined end wall thereof, and with novel drain means at junction of such bottom wall and the inclined wall.

The more specific objects and advantages will become apparent from a consideration of the description following taken in connection with accompanying drawing illustrating an operative embodiment.

In said drawing:

Figure 1 is a view in plan of the improved tub; and

Figure 2 is a central vertical sectional view taken on the line 2—2 of Figure 1.

Referring specifically to the drawing wherein like reference characters designate like or similar parts, a bathtub is shown at 10 which generally may be of any desired shape, size, and materials. As shown the side walls 11 of the tub are vertical as well as is one end wall 12. The other end wall 13 is inclined, and the bottom wall 14 inclines downwardly and away from the base of the straight end wall 12 to the base of the inclined end wall 13.

The water is adapted to be supplied to the tub from any suitable source through a pipe 15, under control of a valve 16 which is arranged to discharge into the tub relatively close to the end wall 12.

An overflow outlet 17 is fastened in the vertical wall 12 adjacent the top in communication with a pipe or conduit 18 which leads to the sewer or other point of discharge.

In the bottom wall 14 relatively close to the inclined wall 13 I provide an outlet connection 19, and lead therefrom a drain pipe 20 which communicates with or empties into the pipe 18. It will be noted that the drain fitting 19 is of such character that when desired the usual plug or stopper may be applied to hold water in the tub 10.

In using the tub, it will be realized, the water is introduced at the valve 16. When washing or flushing the tub, such water will strike the bottom 14 adjacent the wall 12, and will flow over the entire bottom 14, and due to its inclination will drain through the outlet 19 under its own force and the force of gravity. As a result, the flowing water will loosen dirt and foreign matter in the tub and drain the same therefrom as well as it will soapy water and the like, overcoming the necessity of having to force water, as in existing constructions, from adjacent a vertical wall such as 12 toward the other end of the tub, which water thereafter would have to drain toward the vertical end wall before reaching the drain outlet of the tub.

Various changes may be resorted to provided that they fall within the spirit and scope of the invention.

I claim as my invention:

1. A bathtub of the class described having a foot end wall, an inclined end wall opposed thereto, a bottom wall inclining from the foot end wall to the other end wall, an overflow opening in the foot end wall, and a drainage fitting in the bottom wall adjacent its junction with the inclined wall.

2. A bathtub of the class described having a foot end wall, an inclined end wall opposed thereto, a bottom wall inclining from the foot end wall to the other end wall, an overflow opening in the foot end wall, and a drainage fitting in the bottom wall adjacent its junction with the inclined wall, and drainage piping common to said overflow opening and said outlet fitting.
